Filed June 20, 1963, Ser. No. 75,451

Term of patent 14 years

(Cl. D86—10)

FIG. 1

FIG. 2

FIG. 3

FIG. 4

FIG. 5

FIG. 6

FIGURE 1 is a view of one end of a hair drying blower embodying my design;

FIGURE 2 is a view of the opposite end thereof;

FIGURE 3 is a view of one side thereof;

FIGURE 4 is a view of the opposite side thereof;

FIGURE 5 is a top plan view thereof; and

FIGURE 6 is a bottom plan view thereof.

The essential features of the design reside in the rounded shape, downwardly and inwardly slowly sloping sides of the lower portion, gradually upwardly sloping stepped sides of the said lower portion, upwardly sloped sides thereabove at a sharper incline to said stepped sides and vents on a substantial portion of one side of said upwardly sloped sides, all as shown in full lines on the drawing.

I claim:

The ornamental design for a hair drying blower, substantially as shown and described.
